UNITED STATES PATENT OFFICE.

JOSEPH PARKER PRAY, OF NEW YORK, N. Y.

DESIGN FOR A FILE.

SPECIFICATION forming part of Design No. 21,000, dated August 18, 1891.

Application filed April 13, 1891. Serial No. 388,822. Term of patent 7 years.

To all whom it may concern:

Be it known that I, JOSEPH PARKER PRAY, a citizen of the United States, residing at New York city, county and State of New York, have invented and produced a new and original Design for Manicure and Cuticle Files, of which the following is full description, reference being had to the accompanying drawings, forming a part thereof.

10 Figure 1 is a plan view of the design. Fig. 2 is an edge view. Fig. 3 is a cross-section of the blade.

Referring to the drawings, it will be seen that the general contour of the design is knife-shaped—that is, it conforms generally in shape to an ordinary case or table knife. There are points of difference, however. It has a handle and blade separated from each other, as shown in Fig. 1, by a depression or ornamental groove. Beginning at this groove the blade between the points *a b* is entirely covered with a fine lozenge cut, this lozenge cut

being both ornamental and useful. From the point where this lozenge ornamentation stops (see Fig. 1) to the end of the blade there is no 25 ornamentation, and the lower edge between *a* and *b* has an upward deflection of about twenty degrees. This portion of the blade is sharp on the edge and pointed, as shown.

Fig. 2 shows the edge of the design. This 30 edge is also ornamented with lozenge cuts.

Fig. 3 shows a cross-section of the blade. By referring to this figure it will be seen that the blade is wedge-shaped. On both sides of the blade and on the edges the lozenge ornamentation exists, except at the point, as before explained.

What I claim is—

The design for a file herein described and shown.

JOS. PARKER PRAY.
